United States Patent Office

Des. 189,593
Patented Jan. 10, 1961

189,593.

AUTOMATIC MULTI-ELEMENT SPECTROMETER

Alfonso De Pietro, Valhalla, N.Y., assignor to
North American Philips Co., Inc.

Filed June 9, 1958, Ser. No. 51,252

Term of patent 14 years

(Cl. D57—1)

Fig. 1

Fig. 4

FIG. 2.

FIG. 3.

Fig. 1 is a perspective view of an automatic multi-element spectrometer embodying my new design;

Fig. 2 is a side elevational view thereof, taken from the right side of Fig. 1;

Fig. 3 is a side elevational view thereof, taken from the left side of Fig. 1; and

Fig. 4 is a top plan view thereof.

The rear, not shown, is substantially plain.

I claim:

The ornamental design for an automatic multi-element spectrometer, as shown and described.
